UNITED STATES PATENT OFFICE.

RUSH BULLIS, OF MILTON, ROCK COUNTY, WISCONSIN.

ELEVATOR AND DUMP.

SPECIFICATION forming part of Letters Patent No. 532,022, dated January 8, 1895.

Application filed August 23, 1894. Serial No. 521,056. (No model.)

To all whom it may concern:

Be it known that I, RUSH BULLIS, of Milton, in the county of Rock and State of Wisconsin, have invented a new and useful Improvement 5 in Elevators and Dumps, of which the following is a description, reference being had to the accompanying drawings, which are a part of this specification.

My invention has relation to improvements 10 in elevators and dumps, having particular reference to devices for elevating and dumping grain.

The main objects sought to be attained are 15 simplicity in construction and rapidity of action, and in connection therewith strength and durability.

The invention also contemplates the provision of simple means for dumping the load automatically, the construction being such 20 that the dumping can be effected at varying heights.

With the above objects, and others, in view, the invention consists of the devices and parts, or their equivalents, as hereinafter 25 more fully set forth and claimed.

In the accompanying drawings, Figure 1 is a longitudinal vertical sectional view of the complete device. Fig. 2 is a front elevation of the upper portion thereof. Fig. 3 is a view 30 of the rear side of the car; and Fig. 4 is a cross section taken in front of the car.

Like numerals of reference denote like parts throughout the several views.

Referring to the drawings, the numerals 35 5-5 indicate the side beams of a scaffold, connected at their upper ends by a transverse beam 6. The side beams form the outer rails or ways of my improved device, and are connected at regular intervals by cross strips 7.

Intermediate the outer rails 5-5, and secured centrally to the cross strips 7 is a single flat track 8, which extends partially the longitudinal length of the scaffold. This central track is preferably composed of a series of 45 sections, as shown clearly on the drawings, secured end to end in any desirable manner, and thereby permitting the track to be readily shortened or lengthened.

The numeral 9 indicates a car or receptacle, 50 having its rear side inclined, as clearly shown. To this rear side are secured, at opposite edges, angle brackets 10-10, the depending

flanges of which are adapted to fit against the inner sides of the outer tracks or rails 5-5. At the lower end of the inclined rear side is 55 provided an exit opening 11, and bordering the side edges of this opening are angular strips 12-12. At the rear of the depending flanges of these angular strips is journaled a transverse shaft 13, upon which is hung a 60 gravity opening door 14.

In suitable recesses 15-15 at the lower end of the car are mounted rollers 16-16, said rollers, in the travel of the car along the track-way, diminishing the friction materially at 65 the points where the greatest friction would necessarily occur. At the upper end small blocks 17-17 are secured, so as to dispose the car on a perfectly level plane.

Secured to the inner side of the rear piece 70 of the car, near the upper edge thereof, is a doubly grooved pulley 18, and mounted in the upper transverse beam 6 is a similarly grooved pulley 19. An operating cord or rope 20 is attached at its upper end to one of the cross 75 strips 7. This cord is then extended downward and around one of the grooves of the pulley 18, thence upwardly and around one of the grooves of the pulley 19, thence down again and around the other groove of the pulley 18, thence up and around the other groove of pulley 19, and finally extended laterally and downwardly and around a singly grooved pulley 21 mounted in one of the side tracks 5. The free end of the cord or rope is preferably 85 passed around another pulley (not shown) at the base, the cord being in convenient position for manipulation by the operator.

The numeral 22 indicates a hopper for catching the grain as it is discharged from the car. 90 This hopper is provided at one end with hooks 23-23, which are adapted to engage the cross-strip 7 where the central track 8 terminates. Pivoted to the center of the opposite edge of the hopper is a long hook 24, the free end of 95 which is adapted to engage a pin 25 projecting from the next cross-strip above.

In use, my improved device may be arranged in operative position either within a granary or outside thereof. In either case, the scaffold is, preferably, of sufficient length to admit of the upper end thereof extending up to the top of the store room, and to rest against, or be supported by, the beam or rafter 26, as

shown in Fig. 1. When the car is properly adjusted to the trackway, it will be seen that the rear side thereof rests upon the top edges of the side tracks or ways 5—5, while the depending flanges of the angle brackets 10 rest against the sides of the tracks or ways. This latter prevents sidewise displacement of the car. The door 14 bears against the central track 8, and is normally held closed thereby.

10 After the car is filled with grain, and it is desired to elevate the same to an upper story of the granary, a pull is given to the operating cord or rope, and this causes the rapid ascent of the car up the inclined way. As soon as the car reaches the end of the central track 8, however, all support for the door 14 is removed, and of course said door immediately drops by gravity, and the grain is emptied through the exit opening 11. If the

15 hopper 22 is used, the grain, of course, is emptied directly therein, and may be conveyed therefrom to any part of the room by means of a suitable piping coupled to the hopper. I do not wish, however, in any sense, to be understood as limiting myself to the use of my invention in connection with this hopper, as it is obvious that, if preferred, the grain can be emptied directly onto the floor, or may be dumped directly into a suitable

20 pipe, and conveyed thereby to any portion of the room. As soon as the car is emptied of its load, the cord or rope is allowed to slip through the hands of the operator, and the car, of course, will descend the incline by

25 gravity, the door 14 immediately closing automatically as soon as the car begins to descend, by reason of the contact of said door with the end of the central track 8.

If it is desired to dump the load at greater height than that shown in the drawings, of course all that is necessary to be done is to attach another length of the central track 8, while if it is desired to dump at a less height, a length of said track is removed.

40 As the depending flanges of the angular strips 12 fit against opposite edges of the door, it is evident that if the contact of the door with the central track does not have the effect of fully closing said door, said depending flanges will prevent any leakage of the grain during the travel of the car.

45 From the above description, it will be seen that I provide a most simple and rapidly working device, of such construction that the load may be elevated with a minimum amount of power and in which the dumping is effected with the slightest possible loss of time.

50 While I have described my device as having particular reference to means for elevating and dumping grain, yet it is apparent that the same may be conveniently used as an elevator for freight, and in fact all kinds of goods and commodities.

55 Having thus described my invention, what I claim, and desire to secure by Letters Patent of the United States, is—

1. In an elevator and dump, the combina-

tion of an inclined scaffold comprising side tracks or ways and a central rail of less length than the side tracks or ways, a car adapted to travel thereon, said car provided with an opening, a downwardly-swinging door for the opening, said door hinged or pivoted at its lower end to the car and arranged to normally contact with the central track whereby it is held in position for closing the opening, and means for raising and lowering the car, the door being adapted to swing downwardly and empty the load, when the car is raised sufficiently high to bring said door above the upper end of the central track, and said upper end of the central track being adapted to close the door by contact therewith on the return downward movement of the car, over the same tracks of the inclined scaffold substantially as set forth.

2. In an elevator and dump, the combination of an inclined scaffold comprising side tracks or ways and a central rail of less length than the side tracks or ways, said central rail being composed of a series of removable sections, a car adapted to travel thereon, said car provided with an opening, a downwardly-swinging door for the opening, said door hinged to the car and arranged to normally contact with the central track, whereby it is held in a position to close the opening, and means for raising and lowering the car, the door being adapted to swing downwardly and empty the load, when the car is raised sufficiently high to bring the door above the upper end of the central track, and said central track being adapted to close the door on the return downward movement of the car, substantially as set forth.

3. In an elevator and dump, the combination of an inclined scaffold provided with side tracks or ways, a car provided with an exit opening and a door for closing said opening, angle brackets secured to the rear side of said car, the depending flanges thereof bearing against the inner sides of the tracks or ways, and means for raising and lowering the car, substantially as set forth.

4. In an elevator and dump, the combination of an inclined scaffold, provided with side tracks or ways and a central track of less length than the side tracks or ways, a car adapted to travel on the tracks or ways, said car provided with an opening, angular strips secured at opposite side bordering edges of said opening, an inwardly-swinging door for closing the opening, said door fitting between depending flanges of the angular strips and normally held closed by contact with the central rail, and means for raising and lowering the car, substantially as set forth.

5. In an elevator and dump, the combination of an inclined scaffold having side tracks or ways and connecting cross strips, a car adapted to travel thereon, said car provided with an exit opening and with a door for closing said opening, a hopper provided at one edge with a hook or hooks adapted to engage

a cross strip, and at its opposite edge with a pivoted hook adapted to engage the cross-strip next above, and means for raising and lowering the car, substantially as set forth.

5. 6. In an elevator and dump, the combination of a scaffold provided with side tracks or ways, and with an upper connecting cross-beam, a car arranged to travel on the tracks or ways, said car provided with an exit opening, and with a door for closing said opening, a pulley mounted in the car, a pulley mounted in the upper cross beam, a pulley mounted in

one of the side tracks or ways, and an operating cord or rope, said cord or rope having one end fast, and then passed around the respective pulleys of the car and transverse beam, and around the pulley of the side track or way, substantially as set forth. 15

In testimony whereof I affix my signature in presence of two witnesses.

RUSH BULLIS.
